UNITED STATES PATENT OFFICE.

ERNEST VON HAMBACH, OF CHICAGO, ILLINOIS, ASSIGNOR TO HERBERT D. LAFFERTY,
OF OAKLAND, CALIFORNIA.

TIMER.

Application filed March 29, 1920. Serial No. 369,478.

To all whom it may concern:

Be it known that I, ERNEST VON HAMBACH, a citizen of the United States of America, and resident of Chicago, Cook County, Illinois, have invented a certain new and useful Improvement in Timers, of which the following is a specification.

My invention relates to an improvement in timers, and has for its object the provision of an efficient and economical structure which is particularly adapted for use on Ford cars. In cars of this type the space permitted for the timer is very limited and, therefore, difficulties are presented in designing a timer which will operate successfully and yet be of sufficiently small dimensions to fit within the limited space.

The features and objects of my invention will be more clearly understood by first having reference to the accompanying drawings, in which I have illustrated one embodiment of my invention.

Figure 1 is a rear view looking into the casing.

Figure 2 is a transverse sectional view.

Figure 3 is a detail perspective view of the insulating disk or hub which is mounted on the cam shaft.

I have illustrated a shaft 5, which in ordinary practice is the cam shaft of the engine, the inner end of which is slightly reduced in diameter to provide an outwardly-facing shoulder, and upon this inner end a disk or sleeve 6 of insulating material is mounted. A metallic sleeve or lining 7 is preferably inserted between the shaft 5 and the sleeve 6, and the sleeve 6, carrying the insulating sleeve 7, is secured in place by means of the nut 8, said nut serving to jam the metallic sleeve 7 against the shoulder on the shaft and thus at all times maintain an effective electrical contact with the sleeve. The outer end of this sleeve is preferably reduced in diameter, or cone-shaped, as shown at 9, the

base of this cone where it joins the cylindrical part of the sleeve being rounded, as indicated at 10, 10, for purposes hereinafter pointed out. The casing of the timer, which is of the usual standard construction, is indicated at 11. Radially mounted in this casing at equidistant points are a plurality of brush holders 12. Each of these brush holders consists of a single integral member having the inner end thereof bored out to form a

cylindrical space for the reception of the brushes 13, and the outer end of the brush holder being reduced in diameter and threaded and extending through the casing 11. These brush holders are insulated from the casing by an insulating bushing 14 and are held in position by a nut 15 threaded upon the extension 13^a of the brush holder, which extension likewise provides a suitable connection terminal for establishing electrical connection with the brush holder and thus with the brush mounted therein. Mounted within each of the brush holders are suitable spiral springs 16 which press outwardly upon the brushes 13 to thus maintain them in firm and proper contact with the hub 6. Mounted within the rotating hub or rotor 6 is an electrical contact 17 which is connected with the metallic sleeve 7 which is grounded through the engine frame.

In assembling my device, the insulating hub 6 and sleeve 7 are first slid upon the end of the cam shaft 5, and the nut 8 screwed down to hold them in position. The cap or housing 11 carrying the brushes 15 is then placed over the end of the cam shaft. The springs 16 are not of sufficient strength to force the brushes entirely out of the holders but merely press them out a short distance so that when the housing is placed in position, these brushes strike against the inclined surface 9 of the insulating hub and then ride gradually up over this incline onto the horizontal portion of the hub as the housing is forced in position, the housing being held in proper position in any suitable manner.

By my construction, the hub or rotor can be made of comparatively small diameter, and thus the surface speed of this rotor is a great deal less than in constructions where the rotating element is forced by spring pressure against a stationary outer ring as is commonly used in the Ford construction. Where the spring is thus mounted on the revolving member, the stationary ring carrying the stationary contacts must necessarily be of sufficient diameter to permit room for the spring to operate. The speed with which the movable element passes over the stationary element is thereby greatly increased, and as the wear on these parts is proportionate to this engaging speed, it will be seen that by my construction I greatly

reduce the wear both upon the stationary contact members and the revolving contact member.

Furthermore, it often happens that the housing which carries the stationary contacts is not exactly concentric with the cam shaft which carries the rotating contacting element. Where this rotating contact element consists of a contact ball or roller carried around a stationary contact ring, this eccentric positioning of this rotating contact member will cause an unequal wear on the stationary contact ring and thus an uneven operation of the timer. By my construction, however, even though the cam shaft is slightly eccentric with the housing, this will not produce any unequal wear on the revolving hub or rotor, but will at most merely produce slightly greater wear upon one brush than upon another; but such unequal wear will not effect the even operation of the timer, as these brushes are at all times firmly held against the rotor by spring pressure.

Furthermore, it will be seen that in my improved timer there are no parts which require oiling or lubrication which, of course, is a great advantage, as it greatly simplifies the maintenance of the timer.

Furthermore, by having the brushes pressed against the insulating hub by a direct radial thrust, and by having these brushes at all times bear upon a portion of the insulating ring, I insure an even operation of the timer and avoid any jumping of the brushes, thus improving the contact between the brushes and the rotating contact. Furthermore, by the use of brushes having a flat surface contact with the rotating member, I avoid any arcing which arcing tends to burn the contacts and thus reduce the life and efficiency of same.

While I have illustrated and described one particular embodiment of my invention, it will be understood that I do not wish to be limited to the exact construction shown and described, but that various changes and modifications may be made without departing from the spirit and intent of my invention.

What I claim as my invention is:

1. In a timer, a central shaft adapted to be rotated, a sleeve of insulating material carried by said shaft, an electrical contact extending through said sleeve, a housing surrounding said sleeve, a plurality of brush holders mounted in said housing, brushes mounted in said holders, and spring means for forcing said brushes into engagement with said rotating sleeve, said sleeve having at one end thereof a cone-shaped surface which serves to cam the brushes radially outwardly during assembling.

2. In a timer, a shaft adapted to be rotated, a sleeve of insulating material carried by said shaft, an electrical contact carried by said sleeve, a housing surrounding said sleeve and carrying a plurality of brush-holders, each of said brush-holders consisting of a hollow inner member located within said housing and a threaded shank connected to the outer end of said hollow inner member and extending through the wall of the housing to form a connecting terminal on the outside thereof, the outer end of said hollow member serving as an abutment, a brush mounted within said hollow inner member and a spring for actuating said brush, and a binding-nut on said threaded shank for clamping the brush-holder in position on the wall of the housing.

Signed by me at Davenport, Iowa, this 18 day of March, 1920.

ERNEST VON HAMBACH.
